CIRCULAR HAND-KNITTING MACHINE

Sampson Broadwin, Brooklyn, N. Y., assignor to
 Ainslie Knitting Machine Co., Inc., Brooklyn,
 N. Y., a corporation of New York

Application April 21, 1936, Serial No. 75,595

5 Claims. (Cl. 66—6)

This invention relates to circular hand-knitting machines and more particularly to such machines adapted to be used in the home. One object of this invention is to make a circular hand-knitting machine in an economical manner while retaining the maximum number of capabilities of the machine. It is characteristic of machines made in accordance with this invention that there are the minimum number of parts and yet the machine is easily adjusted.

10 In the drawing,

Fig. 1 is a view, largely in vertical section, through a circular hand-knitting machine made in accordance with this invention;

15 Fig. 2 is a detail view in vertical section of the winding end of the machine in operative relation with the driving gear;

Fig. 3 is a plan view of the needle and cam cylinders;

20 Fig. 4 is a horizontal view in inverted section taken just below the cam cylinder on the line 4—4 of Figure 1, showing the cam cylinder, needle cylinder and gear for the cam cylinder;

Fig. 5 is a detail view in vertical section showing the shouldered end of the needle cylinder in operative position;

25 Fig. 6 is a detail view in section on the line 6—6 of Fig. 1, showing how the needle cylinder is held in the frame of the machine;

30 Fig. 7 is a perspective view of the metal insert for the cam path in the cam cylinder; while

Fig. 8 is a plan view of the jaws of the machine showing the manner in which the lugs hold the machine rigid on the table edge.

35 It is desirable that circular hand-knitting machines for home use be inexpensive, easily assembled or adjusted, and that the machines be capable of performing the maximum number of functions. The ordinary knitting machine has a large number of parts which are hard to make and fit together and which of course is entirely too complicated for home use. The machine which is described below is adapted to perform all the necessary functions to permit rapid and economic manufacture of knitted articles in the home and yet it is inexpensive.

40 In the preferred embodiment illustrated in the drawing, the machine has two castings which are the main frame 10 and driving gear 23. This frame has jaws 11 adapted to fit over the edge of a shelf, table, bench or window sill. Passing through the lower of these two jaws is a thumb screw 12 adapted to cause the jaws to grip the table and hold the machine securely. Continual 45 operation of the machine sometimes tends to jar

this thumb screw loose, and I therefore provide a lock nut 13 on the thumb screw which engages against the outer side of the lower jaw 11. For convenience I have made this lock nut a wing nut. The axis of revolution of the driving gear 5 of the machine being at right angles to the length of the table or shelf, I have found it desirable to provide means to prevent the machine slewing or turning about the lock nut. For this purpose the vertical face which forms the bottom of the jaw 10 opening has lateral ears 14 projecting lengthwise of the table on either side (see Fig. 8). These ears or lugs 14 when lying close to the edge of the table serve to prevent the machine from swinging on the thumb screw 12 as a center.

15 The casting comprising the main frame 10 of the machine provides direct mountings for a needle cylinder, a cam cylinder and the driving gear, as well as certain additional parts which will be hereinafter described. I will first explain how 20 the cam cylinder is mounted in the main frame. The main portion of the main frame carrying the cylinders extends outwardly from the table, and there is a depending portion 24 which carries the driving gear and some additional parts. This 25 main portion of the frame is hollow, leaving an upper bearing plate 15 and a lower bearing plate 16. The cam cylinder 17 of the machine is supported by the upper bearing plate 15. The cam cylinder can be made out of wood, composition 30 or any other desired material, and consists broadly of a hollow cylinder with a depending sleeve 18 at its lower end which projects through the upper bearing plate 15 of the frame. The depending sleeve 18 fits in a round opening in the 35 upper bearing plate 15 of the frame so as to permit the needle cylinder to revolve. The main body of the cam cylinder rests on the bearing plate 15. Means are provided on the depending sleeve 18 of the cam cylinder for holding the cam cylinder in the opening of the plate 15 and also for transmitting motion from the driving gear to the cam cylinder. In the example shown in the drawing these means consist of a composition gear ring 19 fitting over the lower end of the depending sleeve 18 and a split ring 20 underneath the gear ring lying in a notch 21 in the depending sleeve 18. As long as the split ring 20 is in its notch the gear ring 19 will be held 40 on the depending sleeve 18. In order to insure that the gear ring 19 will not turn with relation to the cam cylinder, there is a flat surface 22 on one side of the depending sleeve (see Fig. 4). The inner periphery of the gear ring is enlarged 45 to fit the surface 22 snugly.

The gear ring 19 on the cam cylinder is driven by a gear 23 fastened to the depending portion 24 of the main frame by a screw stud 25. The driving gear 23 lies in a vertical plane. The gear teeth on the driving gear 23 are on one side of the periphery, which permits them to engage the teeth of the horizontal gear ring 19 on the cam cylinder. The driving gear can be fastened to the frame by either of two threaded holes 26 in the depending portion of the frame and when the stud fastens the driving gear to the frame by means of the upper threaded hole, the driving gear will be in operative engagement with the gear ring 19. The driving gear can be turned by 10 a handle 27 at its periphery.

The needle cylinder can be made of wood, composition or metal, is mounted inside the cam cylinder and carried by the main frame of the machine. The needle cylinder consists of a hollow tube 29 with open slots 30 around its periphery extending throughout its entire length. The lower end of the needle cylinder passes through the lower bearing plate 16 and an auxiliary bearing plate 31 a short distance above the 15 lower plate 16. This auxiliary plate 31 is a horizontal rib spaced from the lower plate 16 and formed as part of the main frame. There is an opening through this auxiliary plate 31 and another hole or opening through the lower plate 16, 20 these two openings being concentric with the opening in the upper bearing plate 15 carrying the cam cylinder. Whereas the opening through the upper bearing plate 15 is circular, the openings in the auxiliary plate and the lower plate 25 are wedge-shaped. The particular embodiment in the drawing shows an opening which is round except for about 160° which is in the form of a V 32 (see Fig. 6). These openings in the lower plate and the auxiliary plate are too small to 30 permit passage of the depending sleeve 18 of the cam cylinder 17, but they are sized to permit passage of the needle cylinder 29, and the normal position for the needle cylinder is with its lower end projecting through the openings in the lower 35 and auxiliary plates and with its operative end extending up through the needle cylinder. The needle cylinder is gripped between the auxiliary and lower plates by means of a wedging jaw 33, which presses against the needle cylinder on the side opposite the wedge 32, thereby causing the needle cylinder to be gripped between the wedge and the jaw. This jaw is moved by a thumb screw 34 mounted in the outer wall of the main frame 10 as shown in Fig. 6.

The machine is equipped with latch needles 35 adapted to move vertically in the slots 30 of the needle cylinder, these slots being of such depth that the operating butts 36 of the needles project outwardly beyond the needle cylinder into the 40 cam cylinder. The inner surface of the cam cylinder fits the needle cylinder so cam paths have to be provided in the cam cylinder for the operating butts of the needles. These cam paths are constructed by cutting a diagonal slot 37 through 45 the cam cylinder from one side to the other. The slot occupies a width greater than that of the needle cylinder but not sufficient to cut the cam cylinder entirely into separate top and bottom portions. In the examples shown in the drawing this slit is at about a 45° angle with the horizontal. For ease in manufacture and lightness of the cam cylinder, it may be desirable not to use a metal which will be hard enough to withstand the wear on this cam path. If a soft material is 50 used to make the cam cylinder it is therefore

necessary to provide bearing plates in this slot. In the example shown in the drawing, the bearing plates for the slot 37 consist of a metal insert 38 such as shown in Fig. 7. This insert consists of a metal plate folded over on itself so that one leg provides a lining for the lower side of the slot and the other leg provides a lining for the upper side of the slot. In the drawing these legs are designated by the reference characters 39 and 40 respectively. Each such leg or plate is of course 10 cut out at the center to permit insertion of the needle cylinder. It will be obvious that as the cam cylinder is revolved while the needle cylinder stands still, the needle butts 36 will be forced to travel upwardly on one side of the needle cylinder and downwardly while on the other side. If at any time this insert 38 becomes worn, it is very simple to substitute another one.

The means by which needles are inserted or removed is very simple. At one point on the inner periphery of the cam cylinder there is a vertical groove from the top of the cylinder down to the insert 38, and there is a notch in the upper leg of the latter. This groove and notch are sufficiently large to permit passage of the operating 20 butt 36 of any needle which is inserted in a slot 30 in the needle cylinder. The length of stitch drawn is determined in this machine by the relative elevations of the needle and cam cylinders. To get the correct length of stitch it is necessary 25 to vary the height of the needle cylinder, and this is done by loosening the thumb screw 34 and its movable jaw 33, adjusting the height of the needle cylinder and once more tightening the jaw 30 against the cylinder.

The knitting yarn is presented to the needles by a yarn guide 43 which consists of a wire with a loop or eye one end of which wire is stuck in a hole in the top of the cam cylinder 17. This eye is just a small distance above the hooks of the 40 needles when at their uppermost point of travel, and circumferentially the eye shown in the drawing is about 45° in advance of the point where the needles are at their highest elevation. The yarn can come to this guide 43 either from spools 45 44 carried around on the cam cylinder by a bent wire support 45, or from a cone set on the floor or table. From this supply the yarn goes through central eyes 49, 48 formed in a bent wire yarn stand 46 carried by the main frame 10 of the 50 machine. In the example shown in the drawing, this wire stand 46 has its lower end screwed into the upper jaw 11 of the main frame by means of a winged lock nut 47. By adjusting the wire with one hand and manipulating this lock nut 55 with the other, the upper end of the wire stand containing the eyes 48 and 49 can be properly positioned over the top of the needle cylinder a short distance above the yarn guide 43. The positioning of these eyes 48 and 49 is such that 60 the open eye 48 is directly above the center of the needle cylinder, and when the open eye is in this position the closed eye 49 will be slightly eccentric to the axis of the needle cylinder. A yarn coming from the cone is threaded through the 65 closed eye 49, then the open eye 48 and thence to the yarn guide 43. In the construction shown in Fig. 1, however, the knitting yarn is coming from the spool 44 rather than from a cone threaded through the eyes 49, 48. The purpose of feeding 70 the knitting yarn from the spool 44 carried by the cam cylinder is to permit the manufacture of a knitted tube having a filler or filling of cotton roving, or any other similar inexpensive yarn. In this case the filler 50 is threaded through the 75

eyes 49, 48 and thence directly into the inside of the needle cylinder. The knitting yarn—due to the fact that the bent wire support 45 carrying the spool 44 is only about 120° separated from the yarn guide 43—passes from the spool to the yarn guide 43 to one side of the filler. If it is desired to use two yarns in such knitting, a second wire support 45 can be placed on the cam cylinder diametrically opposite the first mentioned support 45, and both yarns can go to the one guide 43.

In pulling the yarn through the old loops in knitting on this machine, the ordinary way to get the proper length of stitch is to cause the hook of the needle to go into its slot 30, as shown in the upper end of Fig. 1. The horizontal dotted line just above the top of the needle cylinder represents the position of the stitches already formed, and the dotted line going down through the 15 needle cylinder represents the finished fabric. Since the ends of the slot are not enlarged but are of uniform width throughout their length, some means must be provided to prevent a heavy yarn catching in the slot when the needles pull the 20 loop down into the slot. To avoid this difficulty I construct the other end of the needle cylinder in a slightly different manner. Thus the needle cylinder can be reversed end for end, according to which kind of yarn is being used. As shown 25 in Fig. 1, the lower end of the needle cylinder is the one used when knitting with a heavy yarn. At this end there is a ring or shoulder 55 around the inner periphery of the cylinder projecting beyond the slots and main portion of the cylinder. By thus having the inner wall of the cylinder extend above the ends of the slots, the needles do not pull down into the slots when they pull the loops through the old stitches.

Assuming that the machine is to knit a tube 51 with a core 50, the knitting operation is started in the following manner. The machine is first secured to the table or bench by placing the edge of that object in between the jaws 11 and tightening up on the thumb screw 12. The driving gear 23 is mounted in operative relation with the gear ring 19 by screwing the stud 25 in the upper threaded hole 26 on the depending arm 24 of the main frame. The knitting yarn 60 is threaded from the spool 44 on the revolving wire support 45 to the yarn guide 43, and the yarn is caused to wrap itself around the hooks of all the needles once or twice by turning the driving gear 23. The loose end of the yarn is then zig-zagged across the needle cylinder, hooking it over the 55 hooks of a few of the diametrically opposite needles. A starting wire or hook to put a weight on the fabric is then inserted through the center of the needle cylinder and hooked onto the strands lying across the top of the needle cylinder. It is not necessary to have formed any 60 stitches prior to the putting in of the starting hook, as the hook can be fastened on to the zig-zag loose ends spaced across from one diametrically opposite needle to the other. The machine is now turned slowly, observing that all the needle latches are open and that each needle is forming its stitch. The length of stitch being drawn can now be adjusted by loosening the thumb screw 34 and raising or lowering the needle cylinder as 65 needed. This starting wire or hook should have sufficient weight on it to keep tension downwardly on the fabric, thus insuring that the machine will cast off the stitches. As soon as a few courses of stitches have been knit, the filler or core 50 is threaded through the guide eyes 49, 48 and intro-

duced into the upper end of the needle cylinder. By pressing the loose end of this filler down into the cylinder opening and resuming knitting, the filler will thereafter be drawn forward automatically by friction with the knitted tube 51.

The machine which I have invented is capable not only of being used for knitting but also for winding yarn. It is capable of winding yarn from a skein onto a bobbin or cone 52, such for instance as shown in Fig. 2. In order to use the machine for winding the yarn, it is clamped onto the edge of the table or bench in inverted position, that is to say, with the thumb screw 12 on top of the table or shelf. The stud 25 is then removed from the threaded hole 26 nearest the 10 needle and cam cylinders and the driving gear 23 is fastened in its other operative position by screwing the stud 25 into the threaded hole 26 furthest from the needle and cam cylinders. On the end of the arm 24 of the main frame 10 is 15 mounted a revoluble spindle 53. This spindle projects from the end of the arm 24 and is tapered so that the core of the cone 52 can be wedged thereon and revolved with the spindle. Mounted on the inner end of the spindle 53 in 20 the end of the arm 24 is a small gear 54 which is tight on the spindle. This gear is so spaced with relation to the adjacent threaded hole 26 that the gear teeth on the driving gear 23 mesh with the teeth on the gear 54 when the driving gear 25 is in the hole 26 adjacent the gear 54. It therefore follows that revolution of the driving gear 23 will cause revolution of the spindle 53 and of the core 52 of the cone on the spindle.

It will be seen that this machine is very inexpensive to manufacture, has only a few parts and is simple in operation. At the same time its capabilities in knitting are quite extensive, and in addition it has the function of preparing the 35 yarn for the knitting.

What I claim is:

1. A circular hand-knitting machine comprising a frame having concentric openings therethrough and a needle cylinder and an integral cam cylinder adapted to fit in said openings, there being a slot cut through the cam cylinder from one side to the other at an angle from the horizontal but leaving material between the upper and lower parts of the cam cylinder at both sides thereof to act as a complete cam path for the 50 needle butts, in combination with a metal insert in said slot to provide bearing surfaces for the butts.

2. A circular hand-knitting machine comprising a frame having concentric openings therethrough and a needle cylinder and an integral cam cylinder adapted to fit in said openings, there being a straight slot cut through the cam cylinder from one side to the other at an angle from the horizontal but leaving material between the 55 upper and lower parts of the cam cylinder at both sides thereof to act as a complete cam path for the needle butts, in combination with a unitary metal insert in said slot to provide upper and lower bearing surfaces for the butts.

3. A circular hand-knitting machine comprising a frame having concentric openings therein and a needle cylinder and a cam cylinder adapted to fit in said openings, a shoulder on the cam cylinder forming a bearing on the frame, in combination with a driving gear fastened to said frame and a driven gear removably mounted on the cam cylinder and holding it in the frame, adapted to transmit to the cam cylinder rotation imparted by the driving gear.

4. A circular hand-knitting machine comprising a frame having concentric openings therein, two of said openings having wedge-shaped formations, in combination with a needle cylinder adapted to fit into said wedge-shaped openings, and a movable jaw in said frame adapted to grip the needle cylinder against rotation.
5. A circular hand-knitting machine comprising a frame having concentric openings therein, a revolute cam cylinder in the upper opening, a shoulder on said cam cylinder forming a bearing on the frame, a needle cylinder inside the cam cylinder and fitting into the two lowermost openings, said two openings being of round shape, in combination with a movable jaw in the frame adapted to grip the needle cylinder against rotation, a driving gear fastened to said frame and a driven gear removably mounted on the cam cylinder and holding it in the frame, adapted to transmit to the cam cylinder rotation imparted by the driving gear. 5
- 10
10. A circular hand-knitting machine comprising a frame having concentric openings therein, a revolute cam cylinder in the upper opening, a shoulder on said cam cylinder forming a bearing on the frame, a needle cylinder inside the cam cylinder and fitting into the two lowermost openings, said two openings being of round shape, in combination with a movable jaw in the frame adapted to grip the needle cylinder against rotation, a driving gear fastened to said frame and a driven gear removably mounted on the cam cylinder and holding it in the frame, adapted to transmit to the cam cylinder rotation imparted by the driving gear. 10

SAMPSON BROADWIN.
